Primary Examiner — Nathan M Johnston(74) *Attorney, Agent, or Firm* — Panitch Schwarze Belisario & Nadel LLP(57) **CLAIM**

The ornamental design for a medication mixing apparatus, as shown and described.

DESCRIPTION

FIG. 1 is a front top perspective view of a medication mixing apparatus showing our new design;

FIG. 2 is a front bottom perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The broken lines show portions of the design that form no part of the claimed design.

1 Claim, 4 Drawing Sheets# US D917,693 S
